UNITED STATES PATENT OFFICE.

ROBERT A. CARTER, OF PITTSBURG, PENNSYLVANIA, ASSIGNOR OF ONE-HALF TO PHILLIPS, NIMICK & CO., OF SAME PLACE.

PILE FOR THE MANUFACTURE OF SHEETS OF IRON.

SPECIFICATION forming part of Letters Patent No. 377,729, dated February 7, 1888.

Application filed November 24, 1886. Serial No. 219,706. (No model.)

To all whom it may concern:

Be it known that I, ROBERT A. CARTER, residing at Pittsburg, in the county of Allegheny and State of Pennsylvania, a citizen of the United States, have invented or discovered certain new and useful Improvements in Piles for the Manufacture of Iron Sheets, &c., of which improvements the following is a specification.

10 In the accompanying drawings, which make part of this specification, Figure 1 is a plan view of my improved plate or cover for piles. Figs. 2 and 3 are edge views of the plates or covers. Fig. 4 is an end elevation of a pile embodying my invention. Fig. 5 is a similar view showing a modification of the plates or covers.

The invention herein relates to certain improvements in piles for the subsequent manufacture of plates, sheets, bars, &c., and has for its object such a construction and arrangement of the parts forming the pile as will permit of a more thorough permeation of the heat throughout the pile and the escape of the cinder therefrom during the heating operation; and to these ends the invention consists in the construction and combination of parts, substantially as hereinafter described and claimed.

It has heretofore been customary in forming piles to first squeeze the puddled balls to remove the slag and cinder and to impart a suitable shape thereto for subsequent rolling; next, to reduce such shapes into bars in muck-rolls; then to cut the muck-bars into suitable lengths; and, finally, to arrange the cut sections into suitable piles, which are then charged into a heating-furnace. In the practice of my invention, however, the puddled ball is taken directly to a suitable hammer and there hammered out into a plate of any desired size proportional to the size of the pile to be formed. After the plate 1 has been hammered out, as described, a series of grooves, 2 and 3, are formed in one side of the plate, (by placing an iron bar of suitable dimensions across the plate and then forcing the bar into the same any desired depth by blows of the hammer.) The number, size, shape, or angular arrangement of the grooves is not material, but should be such as will permit of the ready permeation of the heat in several direc-

tions throughout the pile in which such plates are incorporated and the escape of slag and cinder therefrom.

In forming piles with plates prepared as above described, one plate is arranged with its grooved surface uppermost, and on this is placed a similar plate with its grooved surface down; or, if these two plates will not form a pile of the desired size, one or more plates, 4, similarly grooved on both sides, as shown in Fig. 4, can be interposed between the upper and lower outside plates, which are technically known as "covers," or any other suitable filling—*e. g.*, muck-bar sections.

As will be observed, the above-described construction and arrangement of the plates and covers will permit of the ready access of the heat to the inner as well as to the outer portions of the pile, thereby insuring not only a more rapid heating of the entire pile, but also a more even distribution of the heat throughout the entire mass.

In lieu of forming the grooved plates under a hammer, as described, the puddled ball may be passed through the squeezers, as is usual, and then rolled to plates of the desired dimensions, and finally grooved by passing the plates through suitably-constructed rolls; but I prefer to form such plates under a hammer, as being more expeditious and cheaper.

As the principal characteristic of the invention herein is such a construction of piles as to permit of the ready permeation of heat into and through the interior of the pile and the escape of cinder or slag therefrom, it is evident that the same purposes may be effected by forming a series of ribs or projections on the face of the plates or covers, as clearly shown in Fig. 5. The projections or ribs may be formed either by forming plates of suitable width or thickness into the plates or covers while hot, by blows of the hammer, or by passing said plates between suitably-grooved rolls, as will be readily understood by those skilled in the art.

I am aware that piles for railroad-rails have been made having a longitudinally-grooved base-slab and muck-iron head-slab, the grooves in said slabs being for the purpose of engaging the flanges of rail-sections forming the body

of the pile; but in such construction no provision is made for the penetration of heat in all directions into the body of the pile, as is attained by the construction claimed by me.

5 I claim herein as my invention—

1. A pile consisting of two or more plates or covers having portions of their surfaces depressed, thereby forming grooves and projections, and arranged with their depressed surfaces adjacent to each other, for the purpose of forming passages through and into the piles, substantially as set forth.

10 2. A pile having, in combination, plates or covers provided with projections and a suitable filling, the plates and filling being ar-

ranged in such relation to each other as to form passages through and into the piles, substantially as set forth.

3. A pile having a grooved cover, the grooved surface thereof being arranged adjacent to the body of the pile and in such relation thereto as to form passages through and into the body of the pile, substantially as set forth. 20

In testimony whereof I have hereunto set 25 my hand.

ROBERT A. CARTER.
